UNITED STATES PATENT OFFICE.

CHARLES A. NELSON, OF UTICA, NEW YORK, ASSIGNOR TO SAVAGE ARMS COMPANY,
OF UTICA, NEW YORK, A CORPORATION OF NEW YORK.

FIREARM.

1,176,846.

Specification of Letters Patent. Patented Mar. 28, 1916.

Application filed August 24, 1914. Serial No. 858,255.

To all whom it may concern:

Be it known that I, CHARLES A. NELSON, a citizen of the United States, residing at Utica, in the county of Oneida and State of New York, have invented certain new and useful Improvements in Firearms, of which the following is a specification.

The object of my present invention is to increase the facility of operation, reliability and general efficiency of the means for causing the transfer of the cartridges from the magazine to the breech of a gun of the type in which the cartridges are delivered from the magazine in a direction substantially longitudinally of the axis of the barrel, represented, for instance, in my Patent No. 1,141,256.

I have fully illustrated my present improvements in the accompanying drawings, 20 wherein,

Figure 1 is a longitudinal sectional view of the receiver-portion of a gun having said improvements, showing the transfer and other parts in the position they occupy when the action slide is full back; Fig. 2 is a similar view, showing said parts in the position they occupy when the action slide is partly advanced; Fig. 3 is a similar view, showing said parts in the position they occupy when the action slide is full forward and the gun has been fired; Fig. 4 is an inside elevation of the left half or section of the receiver and the parts carried directly thereby; Fig. 5, 6 and 7 are a side elevation, plan and front elevation of the carrier; Figs. 8 and 9 are a side elevation and a plan of the lifter; Figs. 10 and 11 are a side elevation of a plan of the cartridge stop; Fig. 12 is a plan of the rear part of the action slide; Fig. 13 a view showing the action slide and a stud (12) on the carrier in various positions of the former; and, Fig. 14 is a transverse sectional view of the action slide and carrier in the vertical plane of stud 12.

The receiver or frame *a* comprises a stock section *a'* and a barrel section *a''* which lie face to face when assembled, being interlocked by the mortise and tenon connections *b*, *c* and *d* (Figs. 1 and 4) and held together by the single screw *e* all in a well known manner.

f is the barrel and *g* the magazine tube below the same, into which the cartridges

may be entered in any well known way and then subjected to the backward pressure of 55 the spring plunger *h*.

i is the magazine terminal projecting into the chamber of the receiver and slotted at its upper side in its projecting portion to permit the bodies (but not the heads) of the 60 cartridges to rise although not fully clear rearwardly of the terminal, being substantially the same as the terminal described and claimed in my application Serial No. 737,441, and designed to permit cartridges 65 of various lengths to be handled in the arm.

j is the breech-bolt, carrying the firing-pin *k* and having the forwardly projecting spring-hook cartridge-extractor *l* and opposite hooked projection *m* adapted to receive 70 the head of a cartridge thrust upwardly into their grip (Fig. 2), and also having the breech-up shoulder *n*, coactive with the fixed recoil shoulder *o*, and the depending hook-shaped lug *p* formed with opposite inclined 75 surfaces *p'* and *p''*.

q is the bar (having a sleeve *r* sliding on the magazine tube) of the action slide and *s* the sliding forearm or grip fixed on said sleeve. The rear end portion of the bar *q* 80 is thin at *q'*, so as to possess some resiliency, and thick at *q''*, the thickened portion having on the inside the endless groove or guideway *t* (to be referred to again in detail), the stud *u* and hook *v*. The forward 85 end of the breech-bolt rests at the far side in Figs. 1, 2 and 3 on the action slide and at the rear on stud *u*, being confined against sidewise movement by the two sections *a'* and *a''* of the receiver. When the action- 90 slide is retracted the stud *u* after some lost motion impinges against surface *p'* of hook-lug *p* and cams down the breech-bolt out of breeched-up position, thereupon moving back the latter to the fully open position; 95 when the action slide is returned, after some lost motion again, stud *u* impinges against surface *p''*, drives the bolt home and finally breeches it up.

w is the spring-actuated ejector co-operative with the hook *m* to throw out the empty extracted shells through the opening *x* in a well known manner.

y is the hammer, *z* its spring-pressed thrust-bar, 2 the trigger, 3 the spring- 105 pressed locking bar which holds the trigger

against the notched surface y' of the hammer and forms part of means for manually locking the trigger against retraction when holding the hammer cocked, the hammer being adapted to be moved to the cocked position by the lug p engaging the cam surface y'' (Fig. 4) thereof; and 4 is a manually controlled hook-lever for locking against retraction the action slide unless the stud 10 y''' on the hammer depresses said hook-lever out of locking engagement with the notch q''' of the action slide—*i. e.*, in the forward or firing position of the hammer.

5 is a leaf pivoted on a horizontal axis 15 and spring-held in overlapping position to the cartridge carrier (to be described), when the latter is depressed, retreating into a recess 6 in receiver section a' in response to upward pressure of the carrier when the 20 latter rises.

Those of the foregoing elements that are not found in the Savage Patent No. 839,517 have been described and claimed in my 25 pending application before referred to and are therefore not claimed herein, excepting in certain combinations to be pointed out.

In the improved means for transferring the cartridges from the magazine into position to be breeched the cartridge carrier is 30 moved up and down in both directions under the influence of the action slide, thus avoiding the use of a spring, as in my application referred to, to move the carrier in one direction. Coacting with the carrier to 35 grip the cartridge is the cartridge lifter, which, when the carrier is at its lowest limit of movement, is capable of somewhat further downward movement to allow a cartridge to be introduced from the magazine 40 tube between the gripping portions of the lifter and carrier preparatory to these parts elevating it into position for breeching. Adapted normally to obstruct the discharge end of the magazine tube is a cartridge stop 45 which is displaced out of the obstructing position by the lifter only when the latter is in its lowermost position—where the aforesaid portions of the carrier and lifter are sufficiently spaced to admit a cartridge 50 between them. The carrier, lifter and cartridge stop rise and fall, under the influence of the action slide, substantially as one element, except when the carrier is at its lowest limit of movement, when the lifter and 55 cartridge stop perform the movements peculiar to them independently of the carrier, this being accomplished by a novel association of the three parts and a certain disposition of a spring for influencing the lifter 60 and cartridge stop.

The carrier, 7, fulcrumed on a sleeve 8 arranged in receiver section a' and penetrated by the screw e , at its front end has a cartridge seat 9 and above the rear thereof the 65 overhang 10; depending from its front end

is the curved wall 11 having a slot 11' and serving to limit the downward movement of the carrier, by contact with the under side of the receiver, to a position where seat 9 is aligned with the magazine tube and also serving to prevent delivery of cartridges from the tube except the carrier is thus fully depressed. The carrier, which is bifurcated for the most part, is penetrated by the stud 70 12 projecting therefrom toward the action 75 slide bar q and working in its groove t .

The lifter 13 is fulcrumed on sleeve 8, being fitted between the legs of the carrier, having a slot 14 receiving the stud 12 and being limited in its upward movement relatively to the carrier by said stud, and having a forward tongue 15 to underlie the cartridge, and coact with overhang 10 to grip the cartridge and also to depress the cartridge stop; it has a hump 16 projecting 80 above the rear part of the carrier and formed with the camming surface 16'.

The cartridge stop 17, fulcrumed on a pin 18 in the carrier, has at its front end a fin 19 occupying slot 11' in the carrier and a stop 20 which, by contact with the carrier, limits the upward movement of the cartridge stop in the carrier to a position where the fin projects above the seat 9 of the carrier. 90

Housed between the legs of the carrier and interposed between the lifter and cartridge stop forward of the fulcrum of the former and rearward of that of the latter is a spring 21 which, always under compression, 100 holds the forward end of the lifter elevated to the limit afforded by stud 12 and the forward end of the cartridge stop elevated to the limit afforded by stop 20.

The groove t is continuous, comprising the 105 inclined parallel camming portions t' and t^2 and the upper and lower horizontal portions t^3 , the latter of which is extended rearwardly, as at t^4 .

At t^5 there is a stop or shoulder having 110 the inclined approach t^6 , Fig. 12.

The travel of the stud 12 in groove t , as the action slide reciprocates, is in the direction of the arrows, Fig. 13, where in position I the gun is closed and is ready to fire; in position II the action slide has been retracted; and in position III, IV and V the action slide appears at various stages of return to position I. 115

Opération: The gun being closed, at which 120 time stud u holds the breech-bolt breeched-up and the lifter, cartridge-stop and carrier full down (Fig. 3), the retraction of the action slide accomplishes the unlocking and retraction of the breech-bolt and the release 125 and then the elevation of the parts of the transfer mechanism, so that a cartridge is brought to the position shown in Fig. 1. The ensuing advance of the action slide accomplishes the breeching of said cartridge 130

and the return of the transfer mechanism to the position shown in Fig. 3—the position for receiving a fresh cartridge.

The unlocking and retraction of the breech-bolt and the release and then the elevation of the parts of the transfer mechanism are accomplished as follows: In the retraction of the action slide stud u , first clearing surface p'' and then engaging surface p' , allows the breech-bolt to fall and then drives it backward, resulting in the extraction and ejection of the spent shell in a well known manner by the instrumentalities provided for the purpose; said stud at this time also clears the lifter which, in rising under the pressure of spring 21, on the one hand allows the forward or fin end of the cartridge stop 17 to rise (also under pressure of said spring) until stopped by contact of pin 20 with the lifter, thus immediately blocking the possible premature admission of a cartridge to the cartridge seat of the carrier, and on the other hand grips the butt of the already seated cartridge between itself and the overhang 10 of the carrier; finally, in the latter part of the action slide's movement stud 12 on the carrier is acted upon by the inclined portion t' of the cam groove t , carrier, lifter, cartridge stop and the gripped cartridge moving as one upwardly and pivotally on sleeve 8 as an axis until the carrier abuts the forward end of the breech-bolt (Fig. 1). Once stud 12 fairly begins to mount inclined portion t' of the cam groove the action slide becomes locked by the shoulder t^s against forward movement until the full backward movement has been completed and stud 12 is aligned with the upper groove-portion t^s ; in this way a jam which might result if the transfer mechanism could be returned downward after once being started upward and so cause the upsetting of the cartridge gripped thereby by the next cartridge, is prevented. It will be understood that the spring leaf 5 assists in properly directing the cartridge to its seat in the carrier at the outset and that it also holds its nose depressed in the carrier until approximately the position of Fig. 1 is reached; further, that by bearing against the side of the carrier it frictionally assists in preserving it elevated, *i. e.*, against its stud 12 running (backward) down the incline t' in the now ensuing forward movement of the action slide. When the action slide is now advanced, stud u , by contact with surface p'' , first forward and then breeches-up the breech-bolt, the forward end of the firing pin shoving the cartridge butt out from under overhang 10, the lifter snapping upwardly to the limit afforded by stud 12 and elevating the cartridge into the hold of the gripping means l m on the breech-bolt, which then breeches the cartridge. Stud u

also in its forward travel further engages camming surface $16'$ of hump 16 and thereby depresses lifter, carrier and cartridge stop as substantially one element (*i. e.*, without change in their last relative positions—70 Fig. 2) until the depending wall 11 (which meanwhile has prevented the cartridges in the magazine from being delivered) abuts the receiver and the depression of the carrier is checked, whereupon the lifter is depressed until it bears upon and depresses the forward end of the cartridge stop to allow the rearmost cartridge to enter the carrier with its butt over the tongue of the lifter and under overhang 10; in the present instance, the depression of the lifter is, as stated, actually effected by contact of stud u with hump 16, the inclined portion t^s of the cam groove merely permitting the descending of the stud 12, but it might also be effected by 85 the camming action of portion t^s on stud 12. It will be observed that the breeching-up movement of the bolt and the final depression of the lifter and cartridge stop occur simultaneously as the stud u crowds itself 90 between the breech-bolt and lifter, at which time portion t^s of groove 2 accommodates stud 12. It will also be understood that the thinning of the action slide at q' gives it the needed resiliency to insure the locking 95 action of shoulder t^s .

Having thus fully described my invention, what I claim as new and desire to secure by Letters Patent is:

1. In combination, the frame of a gun, an 100 actuating means movable longitudinally of the gun, and a back-and-forth movable cartridge-gripping transfer means, said actuating means and transfer means having a pair of camming surfaces oblique to the line of travel of the actuating means and affording points of contact of said means with each other and adapted in the movement of the actuating means to cause back and forth movement of the transfer means and on 105 movement of the latter in one direction to press the same against the frame and thereby cause relative movement of its gripping portions.

2. In combination, the frame of the gun, 115 the barrel, the magazine below the barrel, the breech-bolt movable back and forth to and from the barrel and also upwardly into locked engagement with the frame, an up-and-down moving cartridge transfer means, and actuating means movable longitudinally of the gun and in a part of its movement having upward camming action on the breech-bolt and downward camming action on the transfer means. 120

3. In combination, the frame of the gun, the barrel, the magazine below the barrel, the breech-bolt movable back and forth to and from the barrel and also upwardly into locked engagement with the frame, an up- 130

- and-down moving cartridge transfer means, and actuating means movable longitudinally of the gun and in a part of its movement having simultaneous upward camming action on the breech-bolt and downward camming action on the transfer means.
4. In a means for transferring the cartridges from the magazine to the barrel breech of a gun, the combination of a supporting structure, a cartridge-transfer means movable in said structure, and an actuating means for the transfer means movable back and forth, said transfer means and the actuating means each having a camming surface and each also having a stud engageable with the camming surface of the other.
5. In combination, with a supporting structure, mechanism for effecting the transfer of the cartridges from the magazine to the barrel-breech of a gun including a transfer means and reciprocating means adapted on the stroke thereof in one direction to move the transfer means, said mechanism including means to lock the actuating means against movement in the opposite direction when between a definite point in and the end of said stroke.
6. A gun having an action slide movable back and forth between definite limits, and means to lock the action slide during its movement from one of said limits toward the other against movement in the relatively opposite direction.
7. In combination, with a supporting structure, mechanism for effecting the transfer of the cartridges from the magazine to the barrel-breech of a gun including a transfer means and reciprocating means adapted on the stroke thereof in one direction to move the transfer means, said means having interlocking instrumentalities opposing movement of the actuating means in the opposite direction when between a definite point in and the end of said stroke.
8. In combination, with a supporting structure, mechanism for handling the cartridges including a cartridge-moving means and a reciprocating element adapted on its movement in one direction to move said means, said cartridge moving means and the reciprocating element being interlockable to block the movement of said element in the opposite direction when between a definite point in and the end of its movement in one direction.
9. In combination, with a supporting structure, mechanism for effecting the transfer of the cartridges from the magazine to the barrel-breech of a gun including a transfer means and reciprocating means adapted on one stroke thereof to move the transfer means, one of said means having a camming guideway engaged by the other means and said guideway having means between the

ends thereof to block the movement of the actuating means in one direction.

10. In combination, the receiver, the barrel-breech and magazine opening into the receiver, movable mechanism for receiving a cartridge from the magazine and delivering the same in position for breeching including coacting cartridge-holding members, means to move said mechanism, and a magazine delivery controlling device movable in one and controlled by the other of said members.

11. In combination, the receiver, the barrel-breech and magazine opening into the receiver, movable mechanism for receiving a cartridge from the magazine and delivering the same in position for breeching including a pair of cartridge-gripping members, means to transmit movement to said mechanism through one of said members, and a magazine delivery controlling cartridge stop movable in said mechanism and controlled by one of said members.

12. In combination, the receiver, the barrel-breech and magazine opening into the receiver, movable mechanism for receiving a cartridge from the magazine and delivering the same in position for breeching including a pair of cartridge-gripping members, means to transmit movement to said mechanism through one of said members, and a magazine delivery controlling cartridge stop controlled by said member and carried by the other member.

13. In combination, the receiver, the barrel-breech and magazine opening into the receiver, a cartridge carrier movable in the receiver, two members each movable into and out of contact with the carrier and one forming with the carrier a cartridge gripping means and the other forming a magazine delivery controlling cartridge stop, a spring interposed between said members and holding them against the carrier, and means to move the carrier engageable with the first-named member, the latter member being thereupon movable against the second-named member to move the same out of contact with the carrier.

14. In combination, the receiver, the barrel-breech and the magazine opening into the receiver below the barrel, and the up-and-down movable cartridge carrier, a movable magazine delivery controlling device, an actuating member, and a thrust assuming member for the actuating member cushioned on the carrier and engageable with and adapted to actuate the controlling device.

15. In combination, the receiver, the barrel-breech and magazine opening into the receiver below the barrel, an up-and-down movable cartridge carrier, a compressible normally uplifted magazine delivery controlling device, and a common means for mov-

ing the carrier down and depressing the controlling device including a movable member coacting with the carrier to hold the cartridge.

- 5 16. A gun having an action slide movable back and forth, the action slide and a part of the gun lateral of the action slide having interlocking portions adapted on the stroke of the action-slide in one direction to block 10 movement of the slide in the opposite direction when between a definite point in and the end of its stroke in one direction, said portion of the action slide being laterally resilient.
- 15 17. A gun having a one-piece elongated flexible and resilient action-slide member movable longitudinally and also having means to confine said member in one portion of the length thereof against lateral 20 movement, a part of the gun and a portion of said member longitudinally removed from the first-named portion thereof having devices interlocking to block the movement of said member longitudinally in one direction and the second-named portion of said member being free to be laterally flexed from said part of the gun to clear said devices from each other.
- 25 18. In combination, the receiver, the mag-

azine and barrel-breech opening into the receiver, a transfer means movable back and forth in the receiver, cartridge-engaging means frictionally opposing movement of the transfer means, and actuating means for the transfer means movable back and forth, 30 said transfer and actuating means having a pair of camming surfaces affording alternate points of contact of said means with each other in the back and forth movement of the actuating means.

35 19. In combination, the receiver, the barrel breech and magazine opening into the receiver, and coacting movable actuating means and movable transfer means, the latter having movement from cartridge receiving relation to the magazine into position for delivering the cartridge to the barrel-breech, said coacting means including means to block the transfer means against return when between a definite point in said movement and said position.

40 In testimony whereof I affix my signature in presence of two witnesses.
